[57] CLAIM

The ornamental design for a jeans overgarment, as shown and described.

DESCRIPTION

FIG. 1 is an environmental view of a jeans overgarment showing my new design;

FIG. 2 is a front elevational view, with the arms shown in a raised position;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an environmental view of a jeans overgarment showing a second embodiment of my new design; and,

FIG. 9 is a right side elevational view, with the arms shown in a raised position, the left side being a mirror image thereof.

The top, bottom, and rear views are the same in each embodiment.

The broken line showing of a human figure in FIGS. 1 and 8 is for illustrative purposes only and forms no part of the claimed design.
